CLAIM

The ornamental design for a multifunctional wireless charger, as shown and described.

DESCRIPTION

FIG. 1 is a perspective view of a multifunctional wireless charger showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof in a unfolded state; and,

FIG. 9 is another perspective view thereof in a unfolded state.
